UNITED STATES PATENT OFFICE

152,272

DESIGN FOR AN ILLUMINABLE VANITY CASE OR THE LIKE

Fritz Kueppersbusch, Mamaroneck, N. Y.

Application October 5, 1946, Serial No. 133,784

Term of patent 14 years

(Cl. D86—10)

To all whom it may concern:

Be it known that I, Fritz Kueppersbusch, a citizen of the United States of America, residing in Mamaroneck, in the county of Westchester and State of New York, have invented a new, original, and ornamental Design for an Illuminable Vanity Case or the like, of which the following is a specification, reference being had to the accompanying drawing, forming a part thereof.

Fig. 1 is a perspective view of the illuminable vanity case showing my new design in open position;

Fig. 2 is a top view when closed;

Fig. 3 is a front end view of the closed case; and

Fig. 4 is a side view of the same, the other side being identical therewith.

I claim:

The ornamental design for an illuminable vanity case or the like, as shown and described.

FRITZ KUEPPERSBUSCH.
